DRIER FOR SLASHERS

Gaines Lamar Ball, West Point, Ga., assignor to
 Batson-Cook Company, West Point, Ga., a corporation of Georgia

Application March 22 1949, Serial No. 82,789

8 Claims. (Cl. 34—68)

1

This invention relates to an improved dryer for slingers, and more particularly to a dryer utilizing both convection and contact drying.

Slingers are used in the textile industry to apply starch or other liquid preparations to yarn preparatory to winding onto a loom beam for weaving, and a dryer is needed to remove the moisture that is picked up. Dryers of the heated cylinder type, hot air type and radiant heat type have been used with slingers, but all have their inherent disadvantages which are overcome by the dryer of my improved construction.

An object of my invention is to provide a dryer for slingers which utilizes both convection and contact drying.

Another object of my invention is to provide a completely insulated dryer in which a fluid drying medium may be recirculated.

Another object of my invention is to provide a dryer in which the yarn is simultaneously in contact with a fluid drying medium and a heated cylinder.

Another object of my invention is to provide a dryer in which the yarn is subjected to a fluid drying medium prior to contact with a heated drying cylinder.

Another object of my invention is to provide a dryer in which the recirculated fluid drying medium contacts the uninsulated ends of the heated drying cylinders.

Another object of my invention is to provide a dryer in which large guide rolls are used to change the direction of travel of the yarn.

Another object of my invention is to provide a dryer in which the quantity and temperature of fresh drying medium and recirculated drying medium are positively controlled.

Another object of my invention is to provide a dryer in which adjustments may be made without danger of overheating.

Another object of my invention is to provide a dryer in which individual threads of yarn are separated before entering the drying chamber.

Another object of my invention is to provide a dryer in which threads of yarn are prevented from sticking together and in which the drying is efficiently accomplished.

Other and further objects and advantages of my invention will be apparent from the following description taken in connection with the accompanying drawing in which like characters of reference designate corresponding parts throughout the several views, and wherein:

Fig. 1 is a top plan view of a dryer embodying my invention.

2

Fig. 2 is a side elevation of the dryer shown in Fig. 1.

Fig. 3 is a perspective view seen from near the inlet end of the dryer.

Fig. 4 is a perspective view seen from near the outlet end of the dryer.

In the embodiment chosen for illustration, the wet yarn, indicated at 10, is divided by rollers 11, just prior to entering the drying chamber. Other 10 dividing rollers 12 are located within the drying chamber, and these rollers further separate and divide the yarn before it contacts the first drying cylinder 13 which is positioned within the drying chamber and at the end thereof most remote from the entrance port through which the yarn enters the drying chamber. After passing around the drying cylinder 13 for more than 270° of its periphery, the yarn then passes over large guide rolls 14 and 15, each of which substantially reverses the direction of travel for the yarn. Dividing rollers 16 are arranged between the guide rolls 14 and 15 to separate any threads that might have stuck together while in contact with the first drying cylinder 13.

25 The guide roll 15 is positioned near the bottom of the drying chamber and directs the yarn onto a second drying cylinder 17 which is positioned near the bottom of the drying chamber and adjacent the end thereof at which the yarn enters the drying chamber. The yarn then passes around the drying cylinder 17 so as to maintain contact therewith for more than 270° of its periphery, and then leaves the lower surface thereof and progresses tangentially across the bottom of the drying chamber, passes beneath drying cylinder 13, around which it is guided without again contacting the cylinder by guide roller 18 and then passes out of the drying chamber over guide roller 19 located at the end of the drying chamber 30 most remote from the dividing rollers 11.

40 Positioned above the drying cylinder 17, and communicating with the drying chamber by means of a blower housing 20, is a mixing chamber 21. A damper 22 is arranged to control the admission of hot air, or other drying medium, to the mixing chamber 21 over the heating coils 23, and a damper 24 is arranged to control the admission of cold air, or other drying medium, to the mixing chamber. An alternative or supplementary damper 22' may be arranged as shown to control the admission of air over the heating coils 23'. For the purpose of this description, the drying medium to be circulated through the apparatus will be considered to be air, though of course it will be appreciated by those skilled in

the art that other gaseous drying mediums could be employed.

Air from the mixing chamber 21 is blown into the drying chamber by the fan 25 positioned in the blower housing 20, and as the air enters the drying chamber it impinges upon the perforated nozzle plate 26 which lies in substantially parallel relation to the yarn passing between the entrance port and the initial point of contact with the periphery of the first drying cylinder 13. The nozzle plate 26 diffuses the drying air, and as the air passes through the many holes in the plate the yarn is subjected to a soft flow of heated air which passes between the threads at a substantially right angle to the yarn's path of travel. The drying air then sweeps downwardly over the yarn lying on a portion of the surface of each of the drying cylinders 13 and 17, and this portion of its travel is directly opposed to the direction of travel of the yarn over which it is sweeping. In its downward path, the air also again passes between the threads, and its path somewhat follows the path of the yarn which is coursing downwardly between the guide rolls 14 and 15.

A baffle plate 28 arranged partially around the outer rim at each end of the drying cylinder 17 permits the drying air to contact the uninsulated ends of the cylinder, but prevents the drying air from bypassing beneath the cylinder 17. Similarly, a baffle plate 27 arranged partially around the outer rim at each end of the drying cylinder 13 closes the space between the cylinder heads and the walls of the enclosure, but permits air to contact the uninsulated heads of the cylinder 13 and sweep upwardly between the cylinder heads and the walls of the enclosure and into the recirculated air plenum chamber 29 situated above the drying cylinder 13 and arranged in contact with the drying chamber through the ducts provided between the side walls of the enclosure and the heads of drying cylinder 13, as outlined by the baffle plates 27 and the vertical wall 30 which also serves to separate the recirculated air plenum chamber 29 from the mixing chamber 21.

Damper 31 is arranged to control the flow of recirculated air from the chamber 29 into the chamber 21. The recirculated air is heated by radiation and by contact with the heads of the drying cylinder 13, and additional heat may be supplied by heating coils 32, if desired. Air that is not recirculated passes beneath the cylinder 13 and into the exhaust channel 33 between the cylinder 13 and the exit wall of the enclosure, and then to the exhaust fan 34 in exhaust duct 35 which is controlled by exhaust damper 35'. A damper 36 is provided over the cylinder 13 to regulate the flow of air around the top of the cylinder into the exhaust channel; and damper 36' is provided to regulate the flow of air between the chamber 29 and the exhaust channel 33, as desired.

The cylinders 17 and 13 shown in the accompanying drawing are 5 ft. and 7 ft. in diameter, respectively, and are rated at 22 pounds per square inch working pressure. Steam for heating the cylinders is supplied through the axle connections in the customary manner. The use of steam pressures in excess of 100 p. s. i. gauge will raise the temperature of air passing through the steam coils equal to or greater than the cylinder temperature; and temperatures as high as 265° F. can be maintained within most sections of the enclosure, and it may reach 290° F. in the mixing chamber.

The fan 25, which is driven by a suitable source of motive power such as electric motor 37, forces air in excess of 10,000 c. f. m. onto the nozzle plate 26 which distributes the air uniformly to the yarn between the entering port and the first heated drying cylinder 13. The air passes through the yarn into the space between the two heated drying cylinders and around the outside surfaces of the cylinders, thereby increasing the drying rate. Reheating and recirculation of the air within the enclosure enable utilization of the full capacity of the hot air to absorb moisture of evaporation; and air is exhausted only after it has picked up a large amount of moisture, thereby increasing efficiency.

In normal operation, the recirculating damper 31 is fully open, and the cold air damper 24 is completely closed. The inlet of heated air from the outside can be regulated by damper 22 as required to maintain an efficient drying atmosphere within the enclosure. As is customary in dryers of the heated cylinder type, the cylinders 13 and 17 are rotated by the tension in the yarn passing around their peripheries. It is necessary to separate each individual thread before winding onto the loom beam, and the tension required to do this is excessive and injurious if threads are stuck together. Dividing rollers 14 divide the threads before they enter the drying chamber and thereby help prevent sticking and improve air circulation through the yarn. Additional dividing rollers 12 between the enclosure entrance and the first drying cylinder further improve drying efficiency; and as the yarn is partially dried before making contact with the first drying cylinder, the yarn sticking together or to the heated drying cylinder is obviated. The use of large guide rolls 14 and 15, of a diameter approximating one-fourth the diameter of the smaller drying cylinder, to change the direction of travel of the yarn decreases the tension required in the yarn to rotate the equipment and makes possible an arrangement whereby the yarn contacts the drying cylinders for more than 270° of their periphery, thereby increasing drying efficiency.

All exterior surfaces of the enclosure are covered with a suitable insulation material, indicated at 38, to prevent excessive heat loss to the outside air. Enclosure panels, not shown to admit clearer illustration of the essential working parts, may be easily removed for maintenance work within the enclosure. It is frequently necessary to stop or slow down to make adjustments, and during this period it is highly desirable to cool off the enclosure to avoid over drying the yarn. To accomplish this, the hot air damper 22 and recirculating damper 31 are closed while the outside air damper 24 and the exhaust damper 35' are opened, thereby allowing the fans 25 and 34 to pull in cold outside air and force it through the enclosure and thus considerably reduce the enclosure temperature.

It will be obvious to those skilled in the art that many modifications and changes can be made without departing from the scope of my invention as defined in the appended claims.

I claim:

1. A dryer for slashers comprising an enclosure with means defining a drying chamber through which yarn is passed, a mixing chamber, and an exhaust channel; a heated drying cylinder within said drying chamber; means arranged to control the admission of fluid drying medium to said mixing chamber; means arranged to cause fluid

drying medium from said mixing chamber to flow through the yarn within said drying chamber before the yarn reaches said drying cylinder; said drying cylinder being arranged in heat exchange relation with said fluid drying medium in said drying chamber; and means arranged to control the recirculation of fluid drying medium from said drying chamber to said mixing chamber.

2. A dryer for slashers comprising an enclosure with means defining a drying chamber through which yarn is passed, a mixing chamber, and an exhaust channel; a heated drying cylinder within said drying chamber; means for dividing the yarn before it reaches said drying cylinder; means arranged to control the admission of fluid drying medium to said mixing chamber; means arranged to cause fluid drying medium from said mixing chamber to flow through said yarn within said drying chamber before the yarn reaches said drying cylinder; said drying cylinder being arranged in heat exchange relation with said fluid drying medium in said drying chamber; means arranged to control the recirculation of fluid drying medium from said drying chamber to said mixing chamber; and means arranged to control the flow of fluid drying medium from said exhaust channel.

3. A dryer for slashers comprising an enclosure with means defining a drying chamber through which yarn is passed, a mixing chamber, and an exhaust channel; a plurality of heated drying cylinders within said drying chamber; means for dividing the yarn before it reaches the first drying cylinder; means arranged to control the admission of fluid drying medium to said mixing chamber; means arranged to cause fluid drying medium from said mixing chamber to flow through said yarn within said drying chamber before the yarn reaches the first drying cylinder; said drying cylinder being arranged in heat exchange relation with said fluid drying medium in said drying chamber; means arranged to control the recirculation of fluid drying medium from said drying chamber to said mixing chamber; and means arranged to control the flow of fluid drying medium from said exhaust channel.

4. A dryer for slashers comprising an enclosure with means defining a drying chamber, a mixing chamber, and an exhaust channel; a plurality of heated drying cylinders within said drying chamber; means arranged to control the admission of fluid drying medium to said mixing chamber; means arranged to cause fluid drying medium from said mixing chamber to flow through the yarn before it reaches the first drying cylinder; means arranged to control the recirculation of fluid drying medium from said drying chamber to said mixing chamber; and means, between said drying cylinders for changing the direction of travel of said yarn, said last mentioned means comprising rolls having a diameter substantially equal to one-fourth the diameter of one of said drying cylinders.

5. A dryer for slashers comprising an insulated enclosure with means defining a drying chamber through which yarn is passed, a mixing chamber, and an exhaust channel; a plurality of heated drying cylinders within said drying chamber; means for dividing the yarn before it reaches the first drying cylinder; means arranged to control the admission of fluid drying medium to said mixing chamber; means arranged to deliver fluid drying medium from said mixing chamber and to cause said fluid drying medium to flow through said yarn within said drying chamber before the

yarn reaches the first drying cylinder; said drying cylinder being arranged in heat exchange relation with said fluid drying medium in said drying chamber; means arranged to control the recirculation of fluid drying medium from said drying chamber to said mixing chamber; and means arranged to control the flow of fluid drying medium from said exhaust channel.

6. A dryer for slashers comprising an insulated enclosure with means defining a drying chamber, a mixing chamber, and an exhaust channel; a plurality of heated drying cylinders within said drying chamber; means for dividing the yarn before it enters the drying chamber; means within said drying chamber for further dividing the yarn before it reaches the first drying cylinder; nozzle means positioned within said drying chamber and arranged to direct and distribute a flow of fluid drying medium through the yarn before it reaches the first drying cylinder; means arranged to control the admission of fluid drying medium to said mixing chamber; means arranged to deliver fluid drying medium from said mixing chamber and deliver the same to said nozzle means in said drying chamber; means in said drying chamber; means arranged to control the recirculation of fluid drying medium from said drying chamber to said mixing chamber; and means arranged to control the flow of fluid drying medium from said exhaust channel.

7. A dryer for slashers comprising an insulated enclosure with means defining a drying chamber, a mixing chamber, and an exhaust channel; a plurality of heated drying cylinders within said drying chamber; means for dividing the yarn before it enters the drying chamber; means within said drying chamber for further dividing the yarn before it reaches the first drying cylinder; nozzle means positioned within said drying chamber and arranged to direct and distribute a flow of fluid drying medium through the yarn before it reaches the first drying cylinder; means arranged to control the admission of heated fluid drying medium to said mixing chamber; means arranged to control the admission of unheated fluid drying medium to said mixing chamber; means arranged to deliver fluid drying medium from said mixing chamber and deliver the same onto said nozzle means in said drying chamber; means arranged to control the recirculation of fluid drying medium from said drying chamber to said mixing chamber; means arranged to control the flow of fluid drying medium over the first of said drying cylinders in the path of the yarn and into said exhaust channel; and means arranged to control the flow of fluid drying medium from said exhaust channel.

8. A dryer for slashers comprising an insulated enclosure with means defining a drying chamber, a mixing chamber, and an exhaust channel; a plurality of heated drying cylinders within said drying chamber; means for dividing the yarn before it enters the drying chamber; means within said drying chamber for further dividing the yarn before it reaches the first drying cylinder; a perforated nozzle plate positioned within said drying chamber and arranged to direct and distribute a flow of fluid drying medium through the yarn before it reaches the first drying cylinder; a damper arranged to control the admission of a heated fluid drying medium to said mixing chamber; a damper arranged to control the admission of an unheated fluid drying medium to said mixing chamber; means arranged to deliver fluid drying medium from said mixing chamber and

deliver the same onto said nozzle plate in said drying chamber; a damper arranged to control the recirculation of fluid drying medium from said drying chamber to said mixing chamber; a damper arranged to control the flow of fluid drying medium over the first of said drying cylinders in the path of the yarn and into said exhaust channel; and a damper arranged to control the flow of fluid drying medium from said exhaust channel.
